UNITED STATES PATENT OFFICE.

JOSEPH C. BECKLEY, OF DAYTON, OHIO.

GARBAGE-TANK.

968,828.

Specification of Letters Patent. Patented Aug. 30, 1910.

Application filed June 5, 1909. Serial No. 500,273.

To all whom it may concern:

Be it known that I, JOSEPH C. BECKLEY, a citizen of the United States, residing at Dayton, in the county of Montgomery and State of Ohio, have invented certain new and useful Improvements in Garbage-Tanks; and I do declare the following to be a full, clear, and exact description of the invention, such as will enable others skilled in the art to which it appertains to make and use the same, reference being had to the accompanying drawings, which form a part of this specification.

This invention relates to improvements in garbage tanks which are transported on wheels from place to place by the city garbage collector and in which garbage is collected from smaller receptacles located throughout the city. The garbage tank is of such proportions that when filled it may be conveniently lifted from the wagon or truck for the purpose of emptying the same. It is generally the practice in the larger cities to burn the garbage thus collected and crematories are located at desirable distances from the corporation line. To obviate the necessity of using a horse-drawn vehicle to transport the garbage to the crematories, loading stations may be provided within the city and along the line of railroads. At these loading stations the tanks are transferred to cars from the horse-drawn vehicles, it is therefore the object of the present invention to provide a garbage tank which may be conveniently handled in this manner.

A further object of the invention is to provide a tank with a detachable double roll top cover which may be rolled back or opened from either side while the collector is gathering the garbage and which therefore obviates the necessity of the collector going around on the outer side of the tank to fill it. Either half of the top or cover may be thrown back to open the same from either side.

Another object of the invention is to provide other convenient features which will be hereinafter described and claimed.

Preceding a detailed description of the invention, reference is made to the accompanying drawings, of which—

Figure 1, is a side elevation of my improved portable garbage can. Fig. 2, is an end elevation of the device. Fig. 3, is a sectional view on the line *a a* of Fig. 1. Fig. 4, is a

perspective view of the substitute form of cover on a reduced scale. Fig. 5 is a top plan view and a side elevation respectively of the devices for maintaining the tank in a level position when it is being transported from a vehicle to a car. Fig. 6, is a view of the form of handle used to lift the tank during the operation of transferring it.

Throughout the specification and drawings, similar reference characters indicate corresponding parts.

1 designates an oblong rectangular form of garbage tank constructed of a suitable quality of sheet metal and reinforced on its opposite sides by longitudinally-disposed angle bars 6 and 12, the former extend around the ends of the tank as well as serve as abutments for the lower longitudinal edges of the rolling covers 2 and 3 to be again referred to. At each end of the tank are mounted stiffening members 14 which project a suitable distance under the tank and terminate in lugs 15 which are instrumental in holding the tank on the wagon or truck upon which it is transported from place to place. At the upper ends of said stiffening members 14, are mounted flanged pins 13 which are adapted to be engaged by the hooks 17 of a yoke 16 which serves as a handle to lift the tank when it is desired to remove the same from the wagon or truck. During the transferring operation, the tank is held in a horizontal position by pivoted members 18 whose outer ends straddle the vertical sides of the yoke 16. On the front end of the tank are rigidly secured yokes or brackets 20 which are adapted to receive arms extending down from a seat 21 upon which the driver of the wagon sits while transporting the tank from place to place in the collection of the garbage. When the tank is removed from the vehicle, this seat 21 is detached. The ends and sides of the tank project upwardly a suitable distance above the angle bars 6 and the ends are provided with depressions 11 in which a rod 4 rests. This rod extends from end to end of the tank and acts as a pivot for two telescopic roll covers 2 and 3 hereinbefore briefly referred to. These covers are provided with handles 5 and are rolled one within the other from either side of the tank, thus obviating the necessity of the garbage collector going around to the outer side of the tank to fill the same. When both roll covers are in a closed position,

they rest snugly upon the angle bars 6. It will be observed that when cover 2 is thrown back, it will rest upon a handle 5 and will thus be supported in the open position, and when cover 3 is thrown back, it will rest upon angle bars 6 thus only one-half of the top of the tank is exposed at a time, thereby preventing the escape of disagreeable odors as much as possible. The pivot rod 4 is held in the depressions 11 by keepers 7, one end of which is attached to the angle bars 6 on the ends by staples 8, and the other end of which is held by a pin 10 connected to a chain and passing through a bracket 9 and the angle bar 6. When the tank is transferred to a car, for example, after being filled, the roll or telescopic covers 2 and 3 are removed and a separate cover 19 as shown in Fig. 4 may be substituted, said substitute cover being of a flat form allows the tanks to be placed one on top of the other for transportation to and from the crematory. The covers 2 and 3 and 19 being removable, unobstructed entrance may be had to the tank for the purpose of cleansing the same.

Having described my invention, I claim:

1. A portable garbage tank having a two-part telescopic cover adapted to open from either side of the tank and to be utilized in collecting garbage from house to house, a rod forming a pivotal connection between overlapping ends of said cover, the ends of said pivotal rod being supported in recesses in the ends of the tank, and means for maintaining the ends of said rod in said recesses, substantially as specified.
2. A portable garbage tank having a two-part telescopic cover, a rod extending from

end to end of said cover and forming a pivot for the parts of said cover to swing upon, the ends of said rod within the ends of the cover being supported upon the ends of the tank, a keeper pivoted on each end of the tank and adapted to maintain said rod in position, and a flange extending around the outer sides of the tank near the mouth thereof and adapted to engage the parts of said cover to limit the closing movement of said cover.

3. In a portable garbage tank, an oblong rectangular body having a flange on the outer sides thereof adjacent to the mouth thereof, a detachable two-part telescopic cover providing a closure for said tank during the collection of garbage from house to house, a rod extending from end to end of said two-part cover and forming a hinge therefor which enables the parts of said cover to swing in opening or closing to one or the other side of said tank, said rod being detachably supported on the ends of said tank, pins on the ends of said tank adapted to receive a handle by means of which the tank may be conveyed from one means of transportation to another, pivotal yokes on the ends of said tank co-operating to maintain the tank in a level position while being thus conveyed, and means on one end of said tank for supporting a seat, substantially as specified.

In testimony whereof I affix my signature, in presence of two witnesses.

JOSEPH C. BECKLEY.
